UNITED STATES PATENT OFFICE.

JOHN F. DAVIDSON, OF ST. PAUL, MINNESOTA.

SPORT SHOE.

Application filed June 19, 1925. Serial No. 38,137.

The present invention relates to shoes, and more particularly to a sport or skating shoe.

A skating shoe, especially when used by children or youths, is very seldom worn out by the time the user has outgrown the shoe.

An object of the present invention is to make a skating shoe having a removable counter, portions of which may be removed to increase the interior length of the shoe.

In order to attain this object, there is provided, in accordance with one feature of the invention, a leather member shaped to conform to the interior of the counter of the shoe and provided with removable pads. This member is positioned interiorly of the lining of the shoe. A second lining is sewed interiorly of the true lining of the shoe and is left free at the lower edge thereof to permit the lower portion thereof to be raised to insert or remove the padded leather member. A flap of leather may be sewed to the rear of the shoe interiorly of the second lining thereof to form a smooth closure across the rear thereof. An inner sole of comparatively stiff material, such as leather, is removably positioned interiorly of the shoe. The heel portion of the inner sole is forced against the false inner lining and the counter and the toe thereof is forced against the toe of the shoe to hold the parts securely in position.

These and other features of the invention, not specifically mentioned, will be more fully brought out in the following description and the accompanying drawings, wherein:

Figure 1, is a view in longitudinal section through a shoe made in accordance with the present invention.

Figure 2, is a view taken on the line 2—2 of the shoe shown in Figure 1, a pair of supporting straps being crossed over to show the method of securing the same.

Figure 3, is a view on the line 3—3 of Figure 1, showing the structure of applicant's invention only, the remainder of the shoe being of a normal type of construction; and

Figure 4, is a view in perspective of a removable counter made in accordance with the present invention.

Referring to the drawings in detail, a shoe A may be of a normal type of construction, and is provided with a lining 1 which is preferably of soft leather sewed interiorly of the shoe on either side thereof. A piece 2

is sewed interiorly of the lining 1 on each side of the shoe and is stitched across at 3, the bottom portion of each of the pieces 2 being free from any connection with the body of the shoe. A piece 4 is sewed interiorly of the pieces 2 to form a smooth closure across the division 5 between the pieces 2 to prevent possible chafing of the foot of the wearer by the joint intermediate the two pieces 2. The piece 4 is also stitched across at 3, the bottom portion of the piece 4 being free from any connection with the body of the shoe. A false counter B comprises a backing 6 of suitable material, such as leather, shaped as shown in Figure 4. Interiorly of the false counter 6 is sewed a piece of padding 7 which may be of felt, the first piece of padding being sewed to the false counter 6 at 9. Interiorly of the first padding member 7, a second padding member 8 may be sewed at 10 so as to permit the removal of padding member 8 and still leave the padding member 7 secured in position at 9. The padding members are sewed so that the bottom edges thereof are spaced from the inwardly turned lower edge of the false counter 6 to receive an inner sole 17 which is preferably of a stiff material such as leather, and is of a length to exert a pressure rearwardly against the false counter and the bottom portion of the padding members 7 and 8 and forwardly against the toe of the shoe to secure the parts firmly in position within the heel of the shoe. The side pieces 2 and the rear piece 4 are of a length to extend well under the edges of the inner sole 17 to prevent their becoming loosened by friction thereon of the foot of the wearer. Instep securing straps 11 and 12 are provided, each of the straps having the external contour shown in Figure 1, and one of the straps being provided with an incision 13 through which the end of the other strap may be inserted. An incision 14 is also provided in each side of the shoe, the straps being sewed in position interiorly of the shoe, as shown in Figure 2. Buckles 15 are provided exteriorly of the shoe and are sewed to the sole of the shoe as illustrated in Figure 2. The straps are each drawn upward to the position shown in Figure 1, and the foot of the wearer is inserted in the shoe. The strap 11 is inserted in the incision 13 in the other strap and the free end of each of the straps is then passed through an incision 14

2
in the side of the shoe to the position shown in Figure 2, the tongue 15 being first laid along the foot of the wearer, so that the straps are on top of the tongue to prevent 5 chasing the foot of the wearer. The free end of each strap is then passed through a buckle 15 and drawn up to securely retain the foot in position therein.

When the shoe becomes too short, one of 10 the padding members may be removed as follows:

The inner sole 17 is first removed by 15 grasping it at approximately the instep and drawing it upward. This arches the inner sole upward and permits the rear end to be withdrawn from the position shown in Figure 1 to free the lower edges of pieces 2 and 4. The lower portions of the pieces 2 and 4 may be raised to disclose the false 20 counter B and its associated parts. By inserting a knife blade intermediate the padding members 7 and 8 the stitching 10 securing the inner pad may be cut and the pad removed. The counter may then be re- 25 placed in the heel of the shoe, and the pieces 2 and 4 may be smoothly drawn down to enclose the counter. The inner sole may then be placed in position interiorly of the shoe in an upwardly arched position so that 30 the rear edge thereof engages the pieces 2 and 4. The inner sole may then be forced downward to the position shown in Figure 1, the action of the inner sole in drawing the lining pieces 2 and 4 backward under the 35 pad acting to firmly secure the parts in position. As the foot of the wearer increases in size, the second pad 7 may likewise be removed and eventually the leather member 6 may be removed entirely to bring the size 40 of the shoe up to its full normal interior length.

I claim—

1. A shoe of the character described, comprising a body portion, a removable counter member inserted therein, a depending flap of leather forming a cover for said removable counter and extending beyond the lower edge of said counter, and a removable inner sole of a length to exert a pressure between the 45 toe of the shoe and the flap of leather overlying the removable counter to hold the flap of leather and the counter firmly in position.

2. A shoe of the character described, comprising a body portion, a removable counter member inserted therein, a plurality of separately removable pads connected to said counter member, a depending flap of leather secured to the body portion and forming a covering for said removable counter and pads

and extending beyond the lower edge of said counter, and a removable inner sole of a length to exert a pressure between the toe of the shoe and the flap of leather overlying the removable counter to hold the flap of leather and the counter firmly in position. 60

3. A shoe of the character described, comprising a body portion, a removable counter member inserted therein, a flap of leather connected to each side of the body portion of the shoe to depend therefrom and cover the removable counter, each of said flaps extending beyond the lower edge of said counter, a third flap of leather secured intermediate the rearward edges of said first mentioned flaps and also extending beyond the 65 lower edge of said counter, and a removable inner sole of a length to exert a pressure between the toe of the shoe and the flaps of leather overlying the removable counter to hold said flaps of leather and the counter 70 firmly in position.

4. A shoe of the character described, comprising a body portion, a removable counter member inserted therein, separately removable pads connected to said counter member, and a removable inner sole positioned to exert a rearward pressure on the counter member to hold said member and the pads 75 removably connected thereto firmly in position.

5. A shoe of the character described, comprising a body portion, a removable counter member inserted therein, said counter member having an inwardly turned lower edge to rest on the sole of said shoe, a lining member secured to the upper portion of the shoe to depend therefrom and having its lower edge free, and extending beyond the lower inwardly turned edge of the counter, and an inner sole resting upon the inwardly turned lower edge of the counter and the lower edge of the lining member to hold the lining member and the counter firmly in position. 95

6. A shoe of the character described, comprising a body portion, a removable counter member inserted therein, separately removable pads connected to a face of said counter member, a lining member having a free lower edge extending beyond the lower edge 100 of the counter member, said lining member covering said counter member, and a removable sole member engaging said lining member and said counter member to hold the pads firmly in position. 110

In testimony whereof I affix my signature.

JOHN F. DAVIDSON.
